UNITED STATES PATENT OFFICE

161,676

ADJUSTABLE REARVIEW MIRROR

William Berk, New York, N. Y., assignor to Super-site Corporation, New York, N. Y., a corporation of New York

Application February 12, 1949, Serial No. 818

Term of patent 7 years

(Cl. D14—6)

To all whom it may concern:

Be it known that I, William Berk, a citizen of the United States and resident of the city of New York, in the county of New York and State of New York, have invented a new, original, and ornamental Design for an Adjustable Rearview Mirror, of which the following is a specification, reference being had to the accompanying drawing, forming part thereof, in which,

Figure 1 is a front elevational view of an adjustable rearview mirror embodying the new design,

Figure 2 is a side view of the same;

Fig. 3 is a fragmentary rear perspective view of the mirror shown in the preceding figures

with the mirror positioned at a right angle to the axis of its supporting swivel joint.

I claim:

The ornamental design for an adjustable rearview mirror, as shown.

WILLIAM BERK.
